UNITED STATES PATENT OFFICE.

HARRY R. HOLDEMAN, OF LOS ANGELES, CALIFORNIA, ASSIGNOR TO THE J. M. FELDMAN CO., INC., OF LOS ANGELES, CALIFORNIA.

DESIGN FOR A SPANISH-EFFECT LIGHTING-FIXTURE RING.

Application filed April 6, 1927. Serial No. 21,478. Term of patent 3½ years.

To all whom it may concern:

Be it known that I, HARRY R. HOLDEMAN, a citizen of the United States, residing at Los Angeles, in the county of Los Angeles and State of California, have invented a new, original, and ornamental Design for Spanish-Effect Lighting-Fixture Rings, of which the following is a specification, reference being had to the accompanying drawing, forming part thereof.

Figure 1 is a side view and Figure 2 is a plan view of a Spanish effect lighting fixture ring showing my new design.

I claim:

The ornamental design for a Spanish effect lighting fixture ring, as shown.

HARRY R. HOLDEMAN.
